Primary Examiner — Jonathan J Han(74) *Attorney, Agent, or Firm* — Banner & Witcoff, Ltd.**(57) CLAIM**

The ornamental design for a shoe, as shown and described.

DESCRIPTION

FIG. 1 is a side view of a shoe showing my new design; FIG. 2 is a rear perspective view thereof; FIG. 3 is a rear view thereof; FIG. 4 is an opposite side rear perspective view thereof; FIG. 5 is an opposite side view thereof; FIG. 6 is a side view of a shoe showing an alternative embodiment of my new design; FIG. 7 is a rear perspective view thereof; FIG. 8 is a rear view thereof; FIG. 9 is an opposite side rear perspective view thereof; and, FIG. 10 is an opposite side view thereof. The broken lines depicting the remainder of the shoe form no part of the claimed design.

1 Claim, 10 Drawing Sheets(56)
